A. R. WELCH

ELECTRODE HOLDER

Filed May 2, 1925

Inventor

ARTHUR R. WELCH,

By *Jack Richmond*

Attorney

UNITED STATES PATENT OFFICE.

ARTHUR R. WELCH, OF EASTON, PENNSYLVANIA.

ELECTRODE HOLDER.

Application filed May 2, 1925. Serial No. 27,435.

My invention provides certain improvements in electrode holders for use in electric welding. In devising these improvements I have had in view the following objects, 5 namely, simplicity of construction, operation and maintenance; facility of connection for cable or lead, permitting the use of any size cable desired; a system of air cooling so designed as to avoid clogging whereby any 10 required current may be transmitted without excessive heating; to provide positive clamping means of the rotary chuck type thereby insuring easy and rapid manipulation; to provide a chuck head constructed of insulating material thereby eliminating the hazard of arcing and consequent loss of current and depreciation of tool, a common fault due to arcing of metal parts of ordinary holders; and finally to provide a well balanced tool 15 equipped with perfect and complete insulation and providing maximum safety in operation coupled with a wide range of adaptability, for example, admitting of the use of electrode wires of $\frac{1}{16}$ " to $\frac{3}{8}$ " dia. without 20 excessive heating.

With such and other objects in view, the nature, characteristic features and scope of the invention will more readily be understood from the following description taken 25 in connection with the accompanying drawing forming a part hereof and illustrating the preferred embodiment of the invention.

Figure 1 is an elevational view of the complete device broken away to expose the 30 cable connection,

Figure 2 is an elevational view of the conductor element of the holder,

Figure 3 is a section on line 3—3 of Fig. 35 1, and

Figure 4 is a longitudinal sectional view 40 of the chuck head.

According to my invention the main body 45 of the holder is a generally round bar 5 of conducting stock, as copper. The bar 5 is cast or otherwise formed as a one piece construction with one end bifurcated to provide cheeks or jaws 6 between which knives the live portion of terminal 7 of the lead or 50 cable 8; the parts being ultimately secured by a bolt 9. Near the other end of the bar

is a raised threaded area 10 for cooperation with an internally threaded chuck head 11. The latter may be constructed of metal but I prefer to form it of insulating material, as for example bakelite. Its headed extremity 12 is movable towards and away from the flat end of the conducting bar to grip or release the electrode which passes through one or the other pair of eyes 13, 14 according to gage.

A casing 15 of bakelite or other suitable material completely insulates live metal parts and provides sufficient overlap for the chuck head even in the event of more than necessary withdrawal thereof. The casing 65 is secured in fixed relation to the conducting bar 5 by one or more set screws 16 which cooperate with an annular keyway 17.

Another office of the casing 15 is to provide an air chamber for cooling purposes. 70 Hence its inner wall is spaced from the bar and the latter has radial studs or projections 18 to center the casing and maintain the spaced relation. At the terminal end the sleeve or casing is fully open to the 75 passage of air and adequate circulation is afforded by one or more lateral vents 19 near the other end of the casing.

The instant holder was devised after dis- 80 comforting experiences with so called standard holders and has demonstrated marked superiority under heavy service conditions.

Having described my invention, I claim:

An electrode holder, comprising a solid 85 conducting bar formed at one end for attachment of a cable connection and formed at the other end with a threaded seat, and intermediate the ends with radial studs or distance elements, a tubular head of insulating material fitted to the seat and adapted and arranged in conjunction with the head of the bar to grip an electrode, and a one-piece casing sleeve of insulating material surrounding the bar and overlapping the tubular head, said sleeve being open at one 90 end and having lateral vents for unobstructed passage of air for cooling purposes.

In testimony whereof I affix my signature.

ARTHUR R. WELCH.
